UNITED STATES PATENT OFFICE.

WILLIAM ANDREW PETERSEN, OF MONTREAL, QUEBEC, CANADA.

TOOL-HOLDER.

971,556.

Specification of Letters Patent.

Patented Oct. 4, 1910.

Application filed May 16, 1910. Serial No. 561,702.

To all whom it may concern:

Be it known that I, WILLIAM ANDREW PETERSEN, a citizen of Canada, residing at 1120 Des Erables avenue, Montreal, Province of Quebec, Canada, have invented certain new and useful Improvements in Tool-Holders, of which the following is a specification.

This invention relates to tool-holders arranged to be operated by hand or pneumatically and designed principally for use on metal working lathes, and the invention will be readily understood from the following description taken in connection with the accompanying drawing in which:

Figure 1 is a plan of a tool-holder embodying my invention: Fig. 2 a rear elevation of the same: and Fig. 3 a vertical section in the plane of line *a* of Fig. 1.

In the drawing:—1, indicates the tool-holding slide of a lathe or similar tool-carrying metal-working machine: 2, the tool-seat formed thereon; 3, the tool resting on the tool-seat; 4, the tool-clamp, in the form 25 of a lever, disposed over the slide and having one end resting on the tool: 5, serrated inserts of hard steel in the lower face of the tool-engaging portion of the clamp: 6, a bolt projecting up from the slide, near the 30 tool, and passing loosely through the clamp: 7, a nut on this bolt, above the clamp, the lower face of this nut being convex: 8, a washer disposed between the nut and the clamp and having a concave upper face engaged by the nut: 9, a pair of rockers projecting down from the washer and engaging the upper surface of the clamp, there being one of these rockers to the front and one to the rear of the bolt, the two being in one line 35 parallel with the tool, and the lower face of the washer standing clear of the clamp, these rockers forming the fulcrum for the clamp: 10, a helical spring surrounding the bolt between the slide and the clamp and tending 40 to raise the tail-end of the clamp as far as the nut washer will permit: 11, a screw threaded down through the tail-end of the clamp, or the end farthest from the tool, the foot of this screw abutting on the slide, and 45 the upper end of the screw being provided with a head for a wrench and also with a nurl to permit it to be turned by the fingers: 12, a step of hardened steel inserted in the slide at the foot of screw 11, the engagement of the screw and step being of ball-joint character: 13, a pair of rods projecting

from the slide up loosely through holes in the clamp at a point some distance from bolt 6: 14, springs compressed on these rods between the slide and collars on the upper 60 ends of the rods: 15, a cylinder closed at its top and rigidly secured to the clamp at a point between bolt 6 and screw 11: 16, a pipe, to be provided with any suitable valve, for conveying compressed air to the cylinder: 17, a piston in the cylinder: 18, a cam-lever disposed between the slide and clamp and journaled in the slide, the long end of the lever being centrally below the cylinder, and its cam-end being near screw 11: 19, 70 trunnions on the cam-end of the lever: 20, trunnion-bearings formed in the slide, preferably by means of inserted steel blocks: 21, a cam formed on the outer end of the cam-lever and engaging under the clamp: 22, a 75 steel insert in the clamp where it is engaged by the cam: 23, a link connecting the long end of the lever with the piston and passing loosely through a hole in the clamp: and 24, screws employed in securing the cylinder to 80 the clamp.

In Fig. 3 assume, for the present, that screw 11 is absent from the device or that it is screwed up to inactive position. The tool is now seen to be clamped by the powerful 85 action of piston 17 acting through the power multiplying devices represented by the cam-lever and the fulcrum clamp: In practice I secure, by these transmitting devices, a relation of thirty-two to one, that is to say, with 90 a given total pressure on the piston thirty-two times that pressure will be exerted in clamping the tool.

When the pressure is released from over the piston then springs 14 depress the tail-end of the clamp, thus bringing about the elevation of the piston in the cylinder and the release of the tool, spring 10 keeping the clamp up against its fulcrum so that the clamp lifts away from the tool, leaving it 95 free for removal. Owing to the very liberal movement which the device provides for the clamp it is not necessary to make any adjustments preliminary to the pneumatic clamping of the tool. When a tool is used having 100 a shank materially different in size from one for which the device has been adjusted, then nut 7 will require to be adjusted to suit the new condition.

The cam can obviously be so shaped as to 110 yield practically a uniform clamping effect on the tool regardless of ordinary variations

in the angular position of the cam lever. The cylinder can be made of any length desired and it is to be observed that, by reason of its location upon the top of the clamp 5 it does not bring about any interfering side projections of the device and does not interfere with the workman's view of the point of the tool. Furthermore, by reason of the cylinder being carried by the clamp instead 10 of by the slide, the simple removal of nut 7 permits of the ready removal of the clamp with all of its accessories.

If compressed air be not available then 15 screw 11 can be brought into action, in an obvious manner, and without necessity for disconnecting any other parts.

I claim:—

1. A tool-holder comprising, a slide provided with a tool-seat, a bolt carried by the 20 slide near and at right angles to the side of the tool-seat, a clamp engaging loosely over the bolt and having a short end to engage over the tool and a long end projecting away from the bolt and tool-seat, a fulcrum carried by the bolt and engaging over the 25 clamp, a spring upon the bolt between the slide and clamp, a spring coöperating with the slide and clamp and tending to press the long end of the clamp toward the slide, and mechanism for forcing the long end of the 30 clamp in the direction away from the slide, combined substantially as set forth.

2. A tool-holder comprising, a slide provided with a tool-seat, a bolt carried by the 35 slide near and at right angles to the side of the tool-seat, a clamp engaging loosely over the bolt and having a short end to engage over the tool and a long end projecting away from the bolt and tool-seat, a fulcrum carried by the bolt and engaging over the 40 clamp, means for vertically adjusting the fulcrum on the bolt, a spring upon the bolt between the slide and clamp, a spring coöperating with the slide and clamp and tending to press the long end of the clamp toward the slide, and mechanism for forcing the long end of the clamp in the direction 45 away from the slide, combined substantially as set forth.

3. A tool-holder comprising, a slide provided with a tool-seat, a bolt carried by the 50 slide near and at right angles to the side of the tool-seat, a clamp engaging loosely over the bolt and having a short end to engage over the tool and a long end projecting away from the bolt and tool-seat, a collar carried 55 loosely by the bolt above and free from the clamp, rockers projecting from the collar down into engagement with the clamp at points in line with each other and parallel with the side of the tool-seat, an adjusting nut on the bolt over the collar, a spring upon the bolt between the slide and clamp, a spring coöperating with the slide and 60 clamp and tending to press the long end of the clamp and tending to press the long end of

the clamp toward the slide, and mechanism for forcing the long end of the clamp in the direction away from the slide, combined substantially as set forth.

4. A tool-holder comprising, a slide provided with a tool-seat, a bolt carried by the 70 slide near and at right angles to the side of the tool-seat, a clamp engaging loosely over the bolt and having a short end to engage over the tool and a long end projecting away from the bolt and tool-seat, a fulcrum carried by the bolt and engaging over the 75 clamp, a spring upon the bolt between the slide and clamp, a spring coöperating with the slide and clamp and tending to press the long end of the clamp toward the slide, a cylinder mounted upon the top of the 80 clamp and provided with a fluid inlet, a piston in the cylinder, mechanism disposed between the slide and the long arm of the 85 clamp to serve in forcing the long arm of the clamp in the direction away from the slide, and a connection between the piston and said mechanism, combined substantially as set forth.

5. A tool-holder comprising, a slide provided with a tool-seat, a bolt carried by the 90 slide near and at right angles to the side of the tool-seat, a clamp engaging loosely over the bolt and having a short end to engage over the tool and a long end projecting away from the bolt and tool-seat, a fulcrum carried by the bolt and engaging over the 95 clamp, a spring upon the bolt between the slide and clamp, a spring coöperating with the slide and clamp and tending to press the long end of the clamp toward the slide, a cylinder mounted upon the top of the 100 clamp and provided with a fluid inlet, a piston in the cylinder, a cam-lever trunnioned in the slide below the clamp and having its long end below said cylinder, a connection between said piston and the long 105 end of the cam-lever, and a cam on the short end of the cam-lever and engaging under the long arm of the clamp near its end, combined substantially as set forth.

6. A tool-holder comprising, a slide provided with a tool-seat, a bolt carried by the 110 slide near and at right angles to the side of the tool-seat, a clamp engaging loosely over the bolt and having a short end to engage over the tool and a long end projecting away from the bolt and tool-seat, a fulcrum carried by the bolt and engaging over the 115 clamp, a spring upon the bolt between the slide and clamp, a spring coöperating with the slide and clamp and tending to press the long end of the clamp toward the slide, a cylinder mounted upon the top of the 120 clamp and provided with a fluid inlet, a piston in the cylinder, a pair of trunnion-bearings supported by the slide near the end of the long arm of the clamp and having their 125 common axis parallel with the side of the 130

5 tool-seat, a cam-lever trunnioned in said trunnion-bearings, a connection between said piston and the long arm of the cam-lever, and a cam on the short arm of the cam-lever 5 and engaging upwardly against the clamp near the end of its longer arm, combined substantially as set forth.

7. A tool-holder comprising, a slide provided with a tool-seat, a bolt carried by the 10 slide near and at right angles to the side of the tool-seat, a clamp engaging loosely over the bolt and having a short end to engage over the tool and a long end projecting away from the bolt and tool-seat, a fulcrum carried by the bolt and engaging over the clamp, a spring upon the bolt between the slide and clamp, a spring coöperating with the slide 15 and clamp and tending to press the long end of the clamp toward the slide, a cylinder 20 mounted upon the top of the clamp and provided with a fluid inlet, a piston in the cylinder, a pair of open topped trunnion-bearings supported by the slide near the end of the long arm of the clamp and having their 25 common axis parallel with the side of the tool-seat, a cam-lever trunnioned in said trunnion-bearings, a connection between said piston and the long arm of the cam lever, and a cam on the short arm of the cam-lever 30 and engaging upwardly against the clamp near the end of its longer arm, combined substantially as set forth.

8. A tool-holder comprising, a slide provided with a tool-seat, a bolt carried by the 35 slide near and at right angles to the side of the tool-seat, a clamp engaging loosely over the bolt and having a short end to engage over the tool and a long end projecting away from the bolt and tool-seat, a fulcrum carried by the bolt and engaging over the clamp, a spring upon the bolt between the slide and clamp, a spring coöperating with 40

the slide and clamp and tending to press the long end of the clamp toward the slide, pneumatic mechanism adapted to forcibly separate the longer arm of the clamp from the slide, and manual mechanism independent of the pneumatic mechanism for forcibly separating the longer arm of the clamp from the slide, combined substantially as set forth. 45 50

9. A tool-holder comprising, a slide provided with a tool-seat, a bolt carried by the slide near and at right angles to the side of the tool-seat, a clamp engaging loosely over the bolt and having a short end to engage 55 over the tool and a long end projecting away from the bolt and tool-seat, a fulcrum carried by the bolt and engaging over the clamp, a spring upon the bolt between the slide and clamp, a spring coöperating with the slide 60 and clamp and tending to press the long end of the clamp toward the slide, pneumatic mechanism adapted to forcibly separate the longer arm of the clamp from the slide, and a screw coöperating with the clamp and slide 65 and forming manual mechanism independent of the pneumatic mechanism for forcibly separating the longer arm of the clamp from the slide, combined substantially as set forth.

10. In a tool-holder the combination of, a 70 slide having a tool-seat, a clamp having a tool-engaging member disposed over the seat, a clamp fulcrum connected to the slide and engaging above the clamp, a spring compressed between the slide and clamp, a spring 75 urging the non-clamping end of the clamp toward the slide, and means for forcing the non-clamping end of the clamp away from the slide to effect the clamping of the tool.
